COMBINED DRESSER AND CEDAR CHEST

Aaron G. Burnett, Coronado, Calif.

Application March 8, 1954, Serial No. 29,421

Term of patent 14 years

(Cl. D33—6)

Fig. 3

Fig. 4

To all whom it may concern:

Be it known that I, Aaron G. Burnett, a citizen of the United States, residing at Coronado, in the county of San Diego and State of California, have invented a new, original, and ornamental Design for a Combined Dresser and Cedar Chest, of which the following is a specification, reference being had to the accompanying drawings, forming a part thereof, and wherein:

Figure 1 is a front perspective view of a combined dresser and cedar chest showing my design;

Figure 2 is a side elevational view thereof showing the chest cover partially raised;

Figure 3 is a front elevational view thereof showing one of the full length side mirrors fully extended and the other partially extended; and

Figure 4 is a perspective view of the article illustrating the dresser member thereof in an open position.

I claim:

The ornamental design for a combined dresser and cedar chest, as shown.
